UNITED STATES PATENT OFFICE.

ALBERT W. BROWN, OF ELMIRA, NEW YORK.

LIFE-SAVING BUOY.

1,093,381.

Specification of Letters Patent. Patented Apr. 14, 1914.

Application filed November 27, 1912. Serial No. 733,864.

To all whom it may concern:

Be it known that I, ALBERT W. BROWN, of Elmira, in the county of Chemung, in the State of New York, have invented new 5 and useful Improvements in Life-Saving Buoys, of which the following, taken in connection with the accompanying drawings, is a full, clear, and exact description.

This invention relates to certain improvements in life buoys adapted to be carried in quantities by sea-going vessels and other water-craft for preserving lives of passengers in case of marine wrecks or other emergencies necessitating the launching of the 15 passengers into the water.

The main object is to provide a light and easily portable life-saving buoy capable of being stored in a comparatively small compact space on board ship and speedily 20 launched into the water with one or more passengers therein together with a limited quantity of rations, signaling apparatus and other necessary devices for the temporary 25 needs of the occupants with the assurance that the apparatus will float and maintain an upright position in the water and properly house the occupants against undue exposure.

Another object is to make the buoy in the 30 form of frusto-conical sections capable of telescoping one within the other so as to occupy a minimum amount of space in storage or transportation.

A further object is to provide the buoy 35 with a float-controlled air vent above the normal level of the water so as to prevent the entrance of such water into the interior of the shell.

A still further object is to provide means 40 for firmly securing the shell sections together after the passengers are placed therein and also to permit the fastening members to be folded into the interior of one of the 45 sections before said sections are telescoped one within the other for storage or transportation.

Other objects and uses relating to the specific parts of the apparatus will be brought out in the following description.

50 In the drawings Figure 1 is a perspective view of my improved life-saving buoy as launched into the water. Fig. 2 is an enlarged longitudinal vertical sectional view of the same apparatus omitting the 55 weighted end of the righting device and

showing the fastening bolts for connecting the shell sections. Fig. 3 is an inverted plan of the detached buoy showing the means of attaching the weighted righting device. Fig. 4 is an enlarged sectional view through one side of the upper portion of the upper section showing the air vents, float chamber and float therein. Fig. 5 is a top plan of the weighted end of the righting device. Fig. 6 is a perspective view of 60 the upper end of said righting device and Fig. 7 is a horizontal sectional view of the connection between the upper end of the righting device and lower end of the shell.

This life-saving buoy comprises a double 70 conical shell —1— composed of frusto-conical lower and upper sections —2— and —3— of sheet metal or other light, strong and durable material, said sections having their open ends of substantially the same diameter and secured together by suitable fastening means as clamping bolts —4—.

The upper end of the lower section —2— is provided with a reinforcing band or ring —5— rigidly secured to the inner face thereof by brazing or equivalent fastening means and having its upper end extended some distance above the corresponding edge of the section —2— and tapered slightly for receiving the lower open end of the upper 85 section —3— to form a water-tight connection with the section —2—. The lower open end of the upper section is also reinforced by an annular band or metal ring —6— brazed or otherwise secured to the inner face thereof and forming an abutment 90 for the upper end of the ring or band —5—.

The clamping bolts —4— are spaced uniform distances apart within and in close proximity to the inner sides of the shell and 95 are preferably hinged at their lower ends at —7— to suitable lugs on the inner sides of the shell and preferably forming integral parts of the reinforcing band or ring —5—, the upper ends of said bolts being extended 100 through suitable apertures —9— in the top of the upper shell section —3— close to the periphery thereof and are threaded at their upper ends and engaged by thumb nuts —9—, whereby the sections may be drawn tightly 105 together end to end to exclude water at the joint. The length of these clamping bolts —4— is somewhat less than the interior diameter of the shell in the plane of their hinged connections therewith so as to per- 110

mit them to be rocked downwardly into the interior and against the inner sides of the lower section —2— when the shell sections are separated, in which case, the upper section 5 may be inverted and telescoped within the open end of the lower section for compactness in storage or transportation or, if desired, the open end of the upper section —3— may be telescoped with the smaller 10 end of the lower section —2— for the same purpose when the righting device presently described is removed. This righting device 15 is for the purpose of maintaining the buoy in an upright position when launched in the water and preferably consists of a rod —10— having its upper end detachably secured to the central portion of the lower end of the section —2— and its lower end provided with a series of, in this instance three, radially projecting wings —11— spaced equal 20 distances apart circumferentially and constitutes at once a weight and also fins for preventing excessive rotation of the buoy in the water.

25 The upper end of the rod —10— is provided with a dove-tail head —12— slidably interlocked with a dove-tail recess —13— on the bottom of the section —2— and held centrally of said bottom by a cotter pin or key —14— which is passed through an aperture in the bottom of section —2— across the open end of the recess —13— to hold the head 12 against the opposite closed end of said recess, thereby permitting the weighted 30 righting device to be easily and quickly detached and laid alongside of the buoy sections —2— and —3— when the latter are telescoped in storage or transportation.

35 By making the buoy sections —2— and —3— in frusto-conical form, as described, it is evident that a large number of the sections for different buoys may be telescoped together end to end, thereby occupying a minimum space aboard ship.

40 The buoy is constructed so as to receive and house at least two passengers standing on the bottom of the lower section with their shoulders and heads at approximately the largest diameter and above the normal water line when the buoy is launched with the 45 passengers therein, it being understood that the joint at the meeting ends of the sections —2— and —3— will be some distance above such water line when the buoy is filled with 50 passengers, thereby further reducing the liability of entrance of water in the interior 55 of the shell at the joint.

60 The sides of the upper section —3— are provided with a plurality of windows or sight glasses —15— a considerable distance above the water line and approximately on a level with the heads of the occupants so that they may have a clear vision across the surface of the water in which the buoy may 65 be launched, thereby enabling the occupants

to seek relief from land or from an approaching or passing vessel by suitable signals.

In the center of the top of the shell section —3— is placed another but somewhat 70 larger hinged door or window —16— which is held by a suitable clamp —17— accessible from the inside of the buoy to permit the closure to be opened for the passage of distress signals therethrough or for ventilating 75 purposes in a calm sea.

As a further means for ventilating the interior of the shell, I have provided one side of the upper section with a series of vent ports —18— which are covered at the inside 80 of the shell by a suitable housing —19— extending from a point in proximity to the lower side of the vent openings some distance above the same and containing a float valve —20— of any suitable material of less 85 specific gravity than the water and capable of being floated thereby in case of entrance of such water through the vent ports.

The upper side of the vent housing —19— is provided with air ports —21— which are 90 normally opened but are adapted to be closed by the float —20— in case an excessive amount of water should enter the ports —18—. As for example, during a storm when the water might be dashed through such ports, it being understood that as soon as the water recedes from the outer ports —18—, any water which may have accumulated in the vent chamber —19— will readily pass out through such ports, allowing the float to drop to the bottom of the vent chamber, said float having portions of its sides cut away to allow the passage of air from the ports —18— through the chamber —19— and ports —21— into the interior of 100 the shell for ventilating purposes.

When preparing the buoy for the reception of passengers, the lower section —2— is first selected and the weighted righting device —10— attached to the bottom thereof 110 in the manner described after which said section may be hung in any suitable manner in an upright position with its open end uppermost upon the outer side as —A— of the vessel directly over the water.

115 As soon as the lower section —2— is properly supported, the clamping bolts —4— are rocked upwardly to their operative positions and held there while the passengers are being placed within said section, whereupon the cover or upper section —3— is quickly placed in position upon the upper end of the lower section and clamped in place by the bolts —4—. The buoy with the passengers therein is then released or thrown overboard 120 with the assurance that it will float, assuming an upright position by means of the weighted rod —10— aided by the weight of the occupants on the bottom of the shell.

125 It is natural, of course, that before the 130

buoy is launched into the water, in the manner just described, a limited quantity of rations, signals and other necessities for the preservation of the life of the occupants 5 may be placed in the buoy through the gate —16— which is then closed tightly from the inside to prevent the entrance of water into the interior of the shell when launched.

What I claim is:

- 10 1. A life-saving buoy composed of hollow shell sections having their open ends fitted to each other and bolts hinged to the inner sides of one of the sections to swing inwardly and extending through the wall of 15 the other section, and removable means for tightening the bolts.
- 20 2. A life-saving buoy comprising an upper and a lower shell section having their open ends fitted one to the other, bolts hinged to the interior of the lower section to swing inwardly and extending through the top of the upper section and provided with removable exterior means for tightening the bolts.
- 25 3. A life-saving buoy comprising an upper and a lower shell section having their open ends fitted to each other, bolts hinged to the interior of the lower section to swing inwardly and downwardly along the inner 30 sides of said section and extending through the top of the upper section, nuts engaging the outer ends of the bolts, and a lid in the top of the upper section allowing communication with said nuts from the interior of 35 said shell.
- 40 4. A life-saving buoy comprising a hollow shell and a device for holding the shell in an upright position consisting of a rigid rod having sliding interlocking connection with the bottom of the shell, and a weighted member rigidly secured to the lower end of said rod.
- 45 5. A life-saving buoy comprising a hollow shell, a rod having a sliding interlocking connection with the bottom of the shell and having its lower end provided with radially projecting fins rigid therewith.
- 50 6. A life-saving buoy composed of an upper and a lower shell section having their ends fitted to each other, one of said sections provided with a reinforcing band, bolts hinged to said reinforcing band to swing inwardly and extending through the wall of

the other section, and exterior means for tightening said bolts.

55

7. A life-saving buoy comprising upper and lower shell sections having their open ends fitted to each other, the upper section being of less length than the interior diameter of the open end of the lower section, 60 clamping bolts pivotally secured to and within the lower section and extending through the top of the upper section, and nuts engaging the upper ends of said bolts, said bolts being of less length than the interior diameter of the open end of the lower section to allow said bolts to swing inwardly and downwardly within said lower section when the upper section is removed.

65

8. A hollow life-saving buoy having 70 frusto-conical lower and upper ends, the upper section having a ventilating port in one side, a chambered housing on the inner side of said upper section covering said port and provided with a ventilating opening some 75 distance above said port, and a float valve in said chambered housing adapted to be operated by water entering the port for closing said opening.

75

9. A life-saving buoy composed of hollow 80 shell sections having their open ends fitted one to the other, one of said sections provided with a reinforcing band telescoping within the other section.

80

10. A life-saving buoy composed of hollow 85 shell sections having their open ends fitted one to the other, one of said sections provided with a reinforcing band telescoping within the other section, the other section also provided with a reinforcing band 90 adapted to fit to the first named reinforcing band when the sections are fitted together.

85

11. A life-saving buoy comprising a hollow shell having its bottom wall provided with an open-ended groove enlarged inwardly, a righting device having an enlarged end adapted to fit said groove, and means preventing the removal of the end of the righting device from said groove.

95

In witness whereof I have hereunto set 100 my hand this 15th day of November, 1912.

ALBERT W. BROWN.
